CLAIM

The ornamental design for a firearm as shown and described.

DESCRIPTION

FIG. 1 is a back left perspective view of the firearm showing my new design;

FIG. 2 is a front left perspective view thereof;

FIG. 3 is a back right perspective view thereof;

FIG. 4 is a front right perspective view thereof;

FIG. 5 is a left side view thereof;

FIG. 6 is a right side view thereof;

FIG. 7 is a top view thereof;

FIG. 8 is a bottom view thereof;

FIG. 9 is a front view thereof; and,

FIG. 10 is a back view thereof.

The broken lines illustrate portions of the firearm that form no part of the claimed design.
